Primary Examiner — David G Muller(74) *Attorney, Agent, or Firm* — Perkins Coie LLP(57) **CLAIM**

The ornamental design for a urinary catheter assembly, as shown and described.

DESCRIPTION

FIG. 1 is a perspective view of a urinary catheter assembly showing our new design;

FIG. 2 is a left side elevational view of the urinary catheter assembly of FIG. 1;

FIG. 3 is a rear elevational view of the urinary catheter assembly of FIG. 1;

FIG. 4 is a right side elevational view of the urinary catheter assembly of FIG. 1;

FIG. 5 is a front plan view of the urinary catheter assembly of FIG. 1;

FIG. 6 is a top plan view of the urinary catheter assembly of FIG. 1;

FIG. 7 is a bottom plan view of the urinary catheter assembly of FIG. 1; and,

FIG. 8 is another perspective view of the first embodiment of a urinary catheter assembly.

1 Claim, 5 Drawing Sheets(56)
